UNITED STATES PATENT OFFICE.

HARRY I. KLAWANS AND GEORGE KLAWANS, OF CHICAGO, ILLINOIS.

TUFT-MAKING MACHINE.

1,100,746.

Specification of Letters Patent. Patented June 23, 1914.

Application filed March 14, 1912. Serial No. 683,676.

To all whom it may concern:

Be it known that we, HARRY I. KLAWANS and GEORGE KLAWANS, both citizens of the United States, and residents of the city of Chicago, county of Cook, and State of Illinois, have invented a new and useful Tuft-Making Machine, of which the following is a specification.

Our invention relates to machines for manufacturing tufts, and has for its object the provision of a simplified form of such a machine which will have a smaller number of parts, which will work better, which will work quicker, which will make a better tuft, and which will permit of adjustment so as to produce tufts of different sizes. We attain these objects in the mechanism illustrated in the accompanying drawing, in which:—

20 Figure 1 is a side elevation of a tufting machine embodying our invention; Fig. 2 is a front elevation of the feeding and cutting mechanism; Fig. 3 is a plan of the fixed blade of the shears; Fig. 4 is a plan of the movable blade of the shears; Fig. 5 is a fragmental plan of the mechanism shown in Fig. 2; Fig. 6 is a detail, partially in section, of the shaft driving the feeding means; Fig. 7 is a front elevation of a portion of the 25 stapler; and—Figs. 8, 9 and 10, are details of portions of the stapler.

20 Figure 1 is a side elevation of a tufting machine embodying our invention; Fig. 2 is a front elevation of the feeding and cutting mechanism; Fig. 3 is a plan of the fixed blade of the shears; Fig. 4 is a plan of the movable blade of the shears; Fig. 5 is a fragmental plan of the mechanism shown in Fig. 2; Fig. 6 is a detail, partially in section, of the shaft driving the feeding means; Fig. 7 is a front elevation of a portion of the 25 stapler; and—Figs. 8, 9 and 10, are details of portions of the stapler.

Similar reference characters refer to similar parts throughout the several views.

We employ in our invention a stapling machine, such as may be purchased upon the market, and the details of which constitute no portion of our present invention, except as hereinafter specifically described and pointed out. Such a machine has a standard, 1, a staple forming and driving arm, 2, and staple forming and driving head, 3, carried thereby, a mandrel or work table 4, (as shown by dotted lines in Fig. 1) a shaft, 5, for actuating the staple forming and driving mechanism, and a pulley, 6, for transmitting power to the shaft.

Figs. 7, 8, 9, and 10 are details of the stapling mechanism, which differs from the ordinary stapling mechanism only in the following respects. The anvil, 7, (Fig. 10) is rounded, so that when the formers, 8, (Fig. 7) force the staple, 9, over the anvil the head or top of the staple will be rounded instead of square. In order to drive the 55 rounded staple we have rounded the end of the driver, 10, (Fig. 7); and the slots, 11,

in the die for bending the ends of the staple (Figs. 8 and 9) are carried past each other so that the ends of the staple will be lapped.

Our invention consists of means for feeding the material to the stapler, means for cutting the material in proper lengths after it has been stapled, and means for actuating and timing or synchronizing the feeding and cutting means.

The material is led to the stapler by a tube, 12, secured to the mandrel, 4, by a suitable bracket, 13. Upon the front end of the mandrel is a bracket 14, in which is journaled a shaft upon one end of which, right 60 in front of the stapler, is a grooved wheel, 15, in the groove of which are provided teeth, 16. The bracket, 14, has an arm, 17, extending upwardly and forwardly therefrom to which is pivoted a right angle lever, 18, upon the lower end of which is mounted a grooved and toothed wheel, 19, smaller, but similar to, and alining with the wheel, 15. A spring, 20, and adjusting rod 21, through the upper end of the lever 18, serves 65 to adjust the tension with which the wheel, 19, is pressed toward the wheel, 15.

The wheels 15 and 19 comprise the feeding means for the tuft material, and to drive them there is mounted on the other end of 70 the shaft which carries the wheel, 15, a bevel gear, 22, which meshes with a bevel gear, 23, carried upon a shaft 24, journaled in another arm, 25, of the bracket, 13, and which is maintained in its journal by a collar, 26, 75 pinned to said shaft by a pin, 27. The end of the collar, 26, extends beyond the end of the shaft, 24, and is split at 28, for a purpose to be hereafter described.

To prevent the feeding wheels from being 80 rotated too far or from being rotated backward by the stapling operation a brake band, 29, with a friction lining, 30, is secured at 85 31 to the bracket, 14, which encircles a hub, 32, upon the wheel, 15, and a knurl headed bolt, 33, is provided for tightening the band 90 and adjusting the friction.

To the back of the standard, 1, is secured a bracket, 34, which has right and left projections, 35 and 36. The left projection, 36, 95 has pivoted thereto a right-angle lever arm, 37, one end of which has an anti-friction wheel, 38, secured thereto which engages the periphery of a cam plate, 39, secured to the shaft, 5. To the other end of the arm, 37, is pivoted a link, 40, the other end of which is pivoted to another link, 41, the inner end of 100 105 110

which is pivoted upon the lower portion of the projection, 36. Journalized in the lower portion of the projection, 36, is a shaft upon the rear end of which is a ratchet wheel, 42. Said shaft is held in its journal by a split collar, 43, similar to the collar, 26. A pawl, 44, upon the link, 41, is held in engagement with the teeth of the ratchet, 42, by a spring, 45, and a coiled spring, 46, between the link 41, and bracket 36, serves to return the link to its normal position after it has been actuated by the cam, 39. A dog, 47, upon the projection, 36, which is also held in engagement with the ratchet, 42, by a spring, 48, serves to prevent the rotation of the ratchet in the wrong direction. An adjusting bolt, 49, and lock-nut, 50, upon the projection, 36, which extends into contact with the lever 37, serves to adjust the stroke or latitude of revolution imparted to the ratchet. A ball ended shaft, 51, having pins, 52, through the balls extends into the split collars 26 and 43. The projection, 35, which extends to the right from the bracket, 34, has bearings, 53, one above the other so as to rotatably hold the vertically disposed shaft, 54, from the top of which extends an arm, 55, provided upon its end with a roller, 56, adapted to engage the cam, 39. The roller, 56, is maintained in contact with the cam by a spring, 57, wound about the shaft, 54, and secured thereto by the screw, 58, and having its other end caught against the projection, 35. The lower end of the shaft, 54, is extended at right angles to form an arm, 59; to which is secured a rod, 60, which extends forward to the front end of the mandrel, 4, to engage and operate the cutting mechanism now to be described.

Directly below the forward edge of the wheel, 15, is a tubular opening, 61, (shown in Figs. 1, 2, and 5) through which the wheels, 15 and 19, feed the material after it has been stapled. Fitting within this tubular opening is rigidly secured a tube 61^a upon the lower end of which is provided the fixed blade of the shears, 62, shown in Fig. 3. This has a shearing edge, 63, and a stopping edge, 64, which positively severs such fibers as are not cut by the shearing action disposed at substantially right angles to one another, and these edges are so disposed that they are closely adjacent the material as it emerges from the lower end of the tube, 61^a. Rotatably held to the under side of the bracket, 14, by the adjustable bolt, 65, is the movable blade, 66, of the shears (shown in Fig. 4). In Fig. 4 the

movable shear blade is shown separately but with the hole, 67, through which extends the bolt 65 to secure it in place, and the hole, 68, through which extends the rod, 60.

From the foregoing description, taken in connection with the drawings, it will be seen that by modifying the shape of the forming anvil, and driver, of an ordinary stapling machine we have produced a staple of a substantially ring shape suitable for a tuft which must have a generally round section or cylindrical shape. It will also be seen that by providing such a stapling machine with a suitable die for lapping the ends of the staple about the strands of the fabric, we have made an article of much greater strength and substantiality. It will also be seen that by adjustment of the bolt 49, the throw of the lever arm, 37, is either increased or diminished, which either increases or diminishes the revolution of the wheel 15, and thereby regulates the amount of tufting material fed to the cutter or shears, and regulates the length of tuft produced. It will be further seen that with the design of cutter employed a shearing action is secured, which is of considerable importance, as the difficulty of severing a bunch of tufts is well known. And further it will be seen that by driving both the feeding and cutting means from a single cam mounted upon the shaft of the stapling machine, we have, in a very simple manner secured the synchronizing of the various parts so that feeding and cutting will occur successively after the stapling.

Having thus described our invention, what we claim as new and desire to secure by Letters Patent, is:—

A tuft making machine comprising a staple making and driving mechanism, a shaft for driving the same, a cam upon said shaft, a lever system one end of which is actuated by said cam, a dog carried by said lever system, a ratchet engaged by said dog, a set screw adjusting the throw of said lever system, feeding wheels for feeding material to said staple driving mechanism, said feeding wheels being driven by said ratchet, and a cutter for severing the material after it has been fed from said stapler.

In testimony whereof we affix our signatures in the presence of two witnesses.

HARRY I. KLAWANS.
GEORGE KLAWANS.
